**THREADED STUD AND NUT ACTUATED
QUICK-SET CLAMP**

David Mertz, Detroit, Mich.

Application September 8, 1952, Serial No. 308,380

1 Claim. (Cl. 144—303)

The present invention relates to a quick-set clamping device which may be quickly moved into engagement with a piece to be clamped, and thereafter operated to exert relatively great clamping pressure thereon with a minimum of time and effort.

For simplicity and ready explanation, the device is herein illustrated and described as a single clamping member associated with a base having a fixed head or anvil thereon. However, it will be obvious that if desired, two or more clamping devices may be associated together which are independently movable toward and away from each other in the same or parallel or converging T-slots or the like. Thus, three such clamping devices may be used with intersecting T-slots on the bed of a machine tool to position a workpiece with exactitude.

Moreover, a single clamping member may have associated therewith one or more lock members connected together by a plurality of clamping means.

It is an object of the present invention to provide a quick-set clamp characterized by its adaptability to be moved major distances by simple sliding movement and then to be clamped against a workpiece with a minimum of time and effort.

It is a further object of the present invention to provide a quick-set clamp comprising a single actuating device operable sequentially to lock the clamp in approximate clamping position and then to move the clamp in clamping relation.

It is a further object of the present invention to provide a quick-set clamp characterized by its simplicity, ruggedness, ease of operation, and effectiveness.

It is a further object of the present invention to provide a clamp characterized by its ability to develop relatively great clamping pressures while minimizing any tendency to distort the base or frame.

Other objects and features of the invention will become apparent as the description proceeds, especially when taken in conjunction with the accompanying drawings, wherein:

Figure 1 is a plan view of a single embodiment of clamp.

Figure 2 is a vertical median section of the clamp.

Figure 3 is a fragmentary bottom plan view of the clamp.

Figure 4 is a section on the line 4—4, Figure 2.

Figure 5 is a fragmentary perspective of the modified form of nut.

As shown in the simplified embodiment of the invention chosen for illustration, there is provided a base 10 having an elongated slot 12, adjacent one end of which is a fixed head or anvil 14. The outer surfaces of said base at opposite sides of said slot are smooth as indicated at 16. However, at the inner surfaces of said base at opposite sides of said slot, serrated surfaces 18 are provided, and this is most efficiently accomplished by forming the serrations on a separate slotted lock strip 20 which as illustrated is retained in position by set screws 22.

Slidably mounted on the smooth surfaces 16 is a jaw member 24 having a guide key 26 received in the slot 12.

2

The jaw 24 is movable toward and away from the anvil 14 and is adapted to clamp a work piece W. The jaw 24 has an opening 28 extending obliquely therethrough, the opening being laterally enlarged in the plane of Figure 2. Extending through the opening is a socket headed stud 30, which is rockable in the opening 28.

At the inner side of the slot 12 there is provided a lock member 32 which spans the slot and has a serrated surface engageable with the serrations of the surfaces 18 to retain the lock against movement along the slot. As illustrated, the serrations are symmetrical 60° serrations but while this offers some definite advantages, the angle of the serrations may be varied and they need not be symmetrical. The pitch of the serrations in a practical embodiment of the invention was $\frac{1}{16}$ of an inch, but the essential requirement is only that the pitch be related to the longitudinal adjustment of the jaw at each setting such that clamping pressure may be applied by the jaw in any position along the slot.

At its lower side the lock 32 is provided with a recess or seat 34 which is herein illustrated as spherical. Located in the seat 34 is a nut 36, also spherically formed. The nut is thus rockable in the seat. The nut has a slot 38 formed therein, and the end 40 of a set screw 42 enters the slot to hold the nut in place and to prevent rotation.

In Figure 5 there is illustrated at 44 a different form of nut which is cylindrically shaped and is adapted to seat in a correspondingly shaped cylindrical seat. The cylindrical nut 44 of course requires no separate means to prevent its rotation.

The threaded stud 30 engages the nut 36 (or 44) and when rotated by a tool draws the lock 32 and jaw 24 toward each other. When this takes place, the serrations on the lock engage the serrations on the surface 18 and prevent movement of the lock longitudinally of the slot 12. Further actuation of the stud moves the jaw along the surface 16 of the base in a direction to decrease the separation between lock 32 and jaw 24 longitudinally of the slot 12. This is accompanied by rocking of the stud 30 in the plane of Figure 2.

In order to prevent engagement between the serrated surfaces of the lock and lock strip when the stud is loosened and major adjustments of the jaw are required, the lock 32 is provided with spring pressed, round or smooth headed pins 46 which are interposed between the respective serrated surfaces.

In order to provide for automatic relative positioning of the jaw 24 and lock 32 when the stud is loose such as to provide for maximum clamping movement of the jaw 24 after the lock is seated in the serrated surface 18, resilient means are provided to rock the stud 30 in a direction to increase the separation between jaw and lock longitudinally of the slot 12. This comprises a plug 48 of soft metal engaging the stud and received in a bore 50 in the jaw 24. The bore 50 is threaded and receives a threaded plug 52, and between the plugs 52 and 48 is a compression spring 54. This rocks stud 30 clockwise as seen in Figure 2, about an axis adjacent the head of the stud, and assuming the jaw 24 to be stationary, results in movement of the lock 32 to the left in this figure.

From the foregoing it will be seen that when the stud is loosened sufficiently, the entire sub-assembly comprising the jaw, stud and lock, may be moved with substantial freedom along the slot to any desired position. However, when the stud is tightened, the lock first engages the serrated surface 18, and thereafter the jaw is forced to move along the slot in clamping relation.

The angle of obliquity of the stud 30 relative to the plane of the base 10 is herein shown as about 45° but this angle may be varied in accordance with the specific problems to be anticipated. In general however, this angle should be approximately in the range of 40—50°.

Attention is directed to the fact that any tendency to distort the frame when relatively great clamping pressures are exerted is minimized, due to the fact that the jaw 24 and lock 32 overlie each other at the outer and inner sides of the slot 12.

The drawings and the foregoing specification constitute a description of the improved quick-set clamp in such full, clear, concise and exact terms as to enable any person skilled in the art to practice the invention, the scope of which is indicated by the appended claim.

What I claim as my invention is:

A quick set clamping device comprising a base having an elongated slot therein, the surfaces at the outer side of said base at opposite sides of said slot being smooth, the surfaces at the inner side of said base at opposite sides of said slot having series of longitudinally spaced lock seats, a fixed jaw on said base at one end of said slot, a movable jaw member spanning said slot and having portions slidable along said smooth surfaces at the outer side of said base and a guide key slidably received in said slot, an adjustable lock member spanning said slot at the inner side of said base and having parts receivable in said seats to provide for step-by-step positioning of said lock member along said slot, a nut carried by said lock member,

4
said jaw member having an enlarged opening there-through, a headed stud extending through the opening in said jaw member and angularly movable relative thereto in a plane extending longitudinally through said slot and about an axis located substantially at the head thereof, means connecting said nut to said lock member for relative rocking movement in the plane of said slot, means preventing rotation of said nut about the axis of its threads, said stud being threadedly engaged in said nut and extending obliquely to the length of said slot.
